United States Patent Office

Des. 183,955
Patented Nov. 18, 1958

183,955

AUTOMOBILE

Karl Wilfert, Stuttgart-Degerloch, Germany, assignor to
Daimler-Benz Aktiengesellschaft, Stuttgart-Unterturk-
heim, Germany

Application May 4, 1956, Serial No. 41,354

Claims priority, application Germany November 18, 1953

Term of patent 14 years

(Cl. D14—3)

— 2 —

— 3 —

Figure 1 is a rear elevation of an automobile showing my new design;

Figure 2 is a fragmentary top plan view thereof;

Figure 3 is an enlarged perspective view of the combination light shown in Figure 1;

Figures 4, 5 and 6 are cross-sectional views taken along lines 4—4, 5—5, and 6—6 of Figure 3; and

Figure 7 is a side elevation of the automobile shown in Figures 1 and 2.

The dominant features of the automobile in accordance with my design are shown in full lines in the drawing.

I claim:

The ornamental design for an automobile, substantially as shown and described.
